YARN TENSIONING MEANS FOR KNITTING MACHINES

Frank P. Trumplio, Temple, Pa., assignor to Textile Machine Works, Wyomissing, Pa., a corporation of Pennsylvania

Application April 29, 1955, Serial No. 504,774

1 Claim. (Cl. 66—86)

This invention relates to warp knitting machines such as tricot machines, and more particularly to means in such machines to take up the yarns and maintain a constant and uniform tension in the yarns during knitting of the same into fabric.

In textile fabricating machines such as tricot knitting machines and the like, a plurality of sheet of yarns are withdrawn from supply beams and are fed or directed along a predetermined path to the needles or fabricating means where they are formed into fabric. Between the supply beams and the needles the yarns pass over guiding and tensioning means which continuously acts to take up and maintain the yarns under predetermined tension as the needles are operated to knit the yarn into loops. In a usual form, the tensioning means includes a rod extending along the full length of the working portion of the machine, the rod being carried on the ends of levers which are supported for oscillating movement on a shaft fixed in the framework of the machine. The movements of the levers are controlled by springs or the like which act on portions of the levers at the other side of the supporting shaft to resiliently maintain the rod in engagement with the yarns and permit the levers and rod to oscillate to follow the fluctuating demands for the yarns. With this construction the pressure exerted by the yarn and the springs on the levers at opposite sides of the supporting shaft increases the friction in the lever bearings on the supporting shaft which together with the weight mass of the levers and guide rod prevents the sensitive oscillating movements of the parts necessary to maintain the yarns under a uniform tension. This is particularly so in machines operating at high speeds, and results in the uneven feeding of the yarns and the formation of fabric of inferior quality.

In other known forms of tensioning means, the rods are mounted on thin flexible sheet metal plates or other resiliently controlled means fixed on a supporting shaft adjustably mounted in the machine frame. In these devices the shaft is adjustable to vary the initial tension applied to the yarns but there is no way to adjust the resilient means at individual points along the rod to correct variations of tension with the result that an uneven tension is applied to the yarns by different parts of the guide rods.

It is accordingly an object of the invention to provide means in a warp knitting machine for uniformly applying tension on the yarns which means is more economical to manufacture than known types and which will overcome the above mentioned and other difficulties.

Another object of the invention is to provide means for tensioning a plurality of yarns, particularly for use in tricot knitting machines, which means is carried on spaced members which are controlled by resilient means having individual adjustment to permit exertion of uniform tension on all of the yarns.

A further object of the invention is to provide a guide rod for tensioning a plurality of yarns which guide rod is carried on spaced members which are pivoted about bearing surfaces having only point contact to thereby eliminate

2

or reduce to a minimum friction between the bearing surfaces.

With these and other objects in view which will become apparent from the following detailed description of the 5 illustrative embodiment of the invention shown in the illustrative embodiment of the invention shown in the accompanying drawings, the invention resides in the novel elements, features of construction and cooperation of parts, as hereinafter more particularly pointed out in the 10 claim.

In the drawings:

Figure 1 is a cross-sectional view taken transversely through a portion of a tricot knitting machine showing the knitting mechanism and yarn tensioning mechanism 15 according to the invention, dot-and-dash distance breaks being shown to indicate omission of intervening mechanism;

Fig. 2 is a plan view on an enlarged scale of the yarn tensioning mechanism as seen from the left of Fig. 1 and 20 in the direction of the arrow A, certain parts of Fig. 1 being omitted;

Fig. 3 is an elevational view of the mechanism within the arrows 3—3 of Fig. 2, and shown on an enlarged scale relative to Fig. 2;

25 Fig. 4 is a cross-sectional view taken along the line 4—4 of Fig. 3;

Fig. 5 is a view partially in plan and partially in cross section taken substantially on the line 5—5 of Fig. 3;

Fig. 6 is a cross-sectional view taken along the line 30 6—6 of Fig. 4; and

Fig. 7 is a cross-sectional view taken substantially along the line 7—7 of Fig. 1.

Referring to the drawings, and particularly Fig. 1, there 35 is shown a portion of a tricot knitting machine including spring beard needles 10, sinkers 11, a presser member 12 for closing the beards of the needles and front and rear groups of yarn guides 15 for yarns 16. The needles 10, sinkers 11, and presser member 12 are operated at high speeds in the usual manner to form the yarns 16, lapped 40 around the needles by the yarn guides 15, into loops of the fabric. The yarns 16, for the front and rear groups of yarn guides follow separate upper and lower paths, respectively, and are withdrawn from supply beams portions of which are diagrammatically shown at 13 and 14, 45 respectively. The yarns 16 in the lower path pass beneath a rod or shaft 17 which is supported in spaced bearing brackets 20, partially shown in Figs. 1 and 2, carried on a portion 21 of the framework of the machine. From the 50 rod 17 the yarns 16 pass through a comb device 22, carried in the brackets 20, which acts to separate the individual yarns, and from the comb device around a guide rod 24 to the rear group of yarn guides 15. The yarns 16 in the upper path pass beneath a shaft 18 also supported in the bearing brackets 20, through a comb device 23 and over a guide rod 25 to the front group of 55 yarn guides 15.

During the knitting operation of the machine the yarn guides 15 are moved through the needles 10 from their position shown in Fig. 1, then shifted transversely of the 60 needle row and then back to the position of Fig. 1 to lap or loop the yarns around the needles and the needles are simultaneously moved to catch yarns beneath the beards and to form and knit the yarns into loops of the fabric. This movement of the guide members 15 results in a variation 65 in the demand for the yarns thereby tending to cause a periodic increase and decrease in the tension in the yarns between the guide members and the guide rods 24 and 25. In order to maintain a constant tension in the yarns at this time, the guide rods 24 and 25 must be mounted to follow 70 the rapidly varying demands for the yarns. For this purpose, the guide rod 24 for the yarns 16 in the lower path is carried in apertures in side walls 26 of each of a series

of spaced channel-shaped members or arms 27, the side walls being connected by an upper wall 30 (Figs. 3 and 4). A block member 31 is secured to the underside of the upper wall 30 intermediate the ends of each arm 27 by screws 32. Each block member 31 is provided with a V-shaped notch 34 for the reception of a knife-edge 35 forming the apex of a V-shaped portion 36 of a block 37, the knife edge and notch forming a pivot point about which the arms and guide rod 24 rocks during variations in the tension in the yarns. The block 37 is secured by screws 40 to the free end of a support member or bracket 41 having its other end 42 fixed on a rod 43 secured in the bearing brackets 20. As shown in Fig. 2, the end 42 of the bracket 41 is forked to straddle the bearing bracket 20 and thereby maintain the support bracket in fixed position axially of the rod 43. As shown in Fig. 6 the side walls 26 of the arm 27 engages the sides of the block 37 to hold the arm against lateral shifting movement relative to the block.

Tension is applied to each arm 27 by a tension device 45 including a coil spring 48 which is adapted to be pressed against the upper surface of the arm on the opposite side of the pivot point from the rod 24. The block 31 has a portion 50 extending through a slot 51 in the arm 27 and into the end of the spring 48 (Figs. 5 and 6). A rod 52 threadably carried in the block 37 extends through the slot 51 and a corresponding slot in the block 31 and through the spring 48. The spring 48 is positioned on the rod 52 between the arms 27 and a shoulder portion 56 formed internally of one end of a sleeve 57 mounted for sliding movement on the rod 52. The other end of the rod 52 threadably carries lock or jam nuts 60 by means of which the sleeve 57 is adjusted axially of the rod 52 to vary the pressure of the spring 48 on the arm 27 and thereby vary the tension applied by the guide rod 24 to the yarns.

The guide rod 25 for the yarns 16 in the upper path is mounted and tensioned by means which is identical in structure to the arms 27 and tension device 45 and accordingly like reference characters have been applied to the detailed parts thereof. However, in this instance each arm 27 and tension device is mounted on the free end of a support bracket 61 having its other end 62 fixed on a rod 63, secured in the bearing brackets 20. The end 62 is

forked to straddle the bearing bracket 20 to maintain the support bracket in fixed spaced relation on the rod 63 in which it clears the tension device 45 on the support bracket 41 (Fig. 7).

From the foregoing it will be apparent that a light weight efficient tenisoning device is provided by the instant invention attaining the aforesaid objects. Engagement of the knife-edge 35 in the notch 34 provides a substantially friction free pivot point about which each of the arms 27 is rocked to thereby facilitate the rapid movement of the guide rods 24 and 25 in following the fluctuating demands for the yarns during the formation of the yarns into knitted loops.

Of course, the improvements specifically shown and described by which the above results are obtained, can be changed and modified in various ways without departing from the invention herein disclosed and hereinafter claimed.

I claim:

20 In a warp knitting machine having means for supplying a plurality of yarns and means for forming said yarns into a knitted fabric, the improvement comprising means for guiding and for applying tension to said yarns between said supply means and said forming means including a support member, a channel-shaped arm having side walls and a wall joining said side walls, said side walls engaging opposite side faces of said support member, a guide rod for said yarns, apertures in said side walls at one end of said arm for receiving said guide rod, spring means carried on said support member, said spring means acting on the other end of said arm, and means for mounting said arm on said support member for pivotal movement including a member secured to said joining wall intermediate said side walls of said arm and having a notch, and a V-shaped projection on said support member intermediate said guide rod and said spring means for engagement in said notch.
